UNITED STATES PATENT OFFICE.

WILHELM S. VON ESSEN, OF HAMBURG, GERMANY.

IMPROVEMENT IN APPARATUS FOR CLEANING BOILER-TUBES.

Specification forming part of Letters Patent No. 155,127, dated September 15, 1874; application filed August 11, 1874.

To all whom it may concern:

Be it known that I, WILHELM S. VON ESSEN, of Hamburg, in the Empire of Germany, have invented an Improved Apparatus for Cleaning Boiler-Tubes, of which the following is a specification:

This invention relates to the cleaning of fire-tubes of tubular boilers by blowing steam through them; and the invention generally consists in a combination, with the smoke-box and fire-tubes of the boiler, of one or more perforated steam blow-pipes in jointed tubular connection with the steam-space of the boiler, and arranged within the smoke-box, also adjustable, without opening the smoke-box to cool the tubes or admit a reverse draft into or out of line with the fire-tubes, accordingly as it is required to clean the tubes, or to place them out of exposure to the direct action of the fire or hot gaseous products of combustion passing through the tubes.

While numerous changes of construction may be made to suit different kinds or forms of tubular boiler, including attached devices for automatically shutting off the steam from the blow pipe or pipes when the same are thrown out of line with the fire-tubes, it will suffice to describe the invention under one form or modification as applied to a marine-engine boiler, and in which the steam through the blow pipe or pipes is separately turned on or off by hand.

Figure 1 is a broken end view of a marine-engine boiler having my invention applied; Fig. 2, a partly vertical longitudinal section of the same, and Fig. 3 a plan thereof.

A A is the body of the boiler; B B, main fire tubes or chambers; and C C, return fire-tubes, arranged in lines one above the other, and in communication at their one end with the smoke-box D, which is in direct connec-

tion with the chimney E. Within the smoke-box D are one or more steam blow-pipes, G, extending across the smoke-box outside the smoke-box ends of the fire-tubes C C. Such blow pipe or pipes G have their perforations b on their inside faces next to the ends of the fire-tubes C C, and are suitably bent and connected with a frame of movable or sliding pipes, G' G', and a flexible or jointed steam-pipe attachment, H H', which connects with a steam-pipe, I, of the boiler, having a cock, d. This movable frame of pipes is adjustable up or down outside of the smoke-box D, and without opening the doors or lids f of the latter, by means of a chain-and-pulley lift, J, controlled by a perforated stop device, K, to adjust the blow-pipes G into or out of line with the fire-tubes C C, accordingly as it is required to blow steam through the latter for the purpose of cleaning the same on opening the cock d, or of placing said blow pipe or pipes out of the way of all interference with the draft or exposure to the fire passing through the tubes C.

In this way, or by these means, the steam blow-pipes may be put into or out of connection with the fire-tubes C without cooling said tubes or checking the draft through them by opening the doors f for the purpose.

I claim—

The combination, with the smoke-box D and fire-tubes C, of one or more perforated steam blow-pipes, G, made adjustable up or down from the exterior of the smoke-box, and without opening the latter into or out of line with consecutive upper and lower rows of the fire-tubes, substantially as specified.

WILHELM S. VON ESSEN.
